PIPE COATING APPARATUS

Albert G. Perkins, Warsaw, N. Y.

Application May 13, 1933, Serial No. 670,919

19 Claims. (Cl. 25—38)

This invention relates to improvements in pipe coating apparatus for applying a protective coating or lining to the inner walls of steel pipe lines.

One of its objects is the provision of a reliable efficient apparatus of this character which is designed to travel through the pipe line and as it does so automatically apply an even and durable coating of plastic material onto the pipe wall by centrifugal force and at the same time troweling the coating so applied.

Another object of the invention is to provide simple and effective troweling means which are so designed and constructed as to be readily controlled from the operating end of the machine to bring the trowels into and out of engagement with the pipe wall.

A further object is to provide a coating apparatus of this character having, in combination with the plastic applying means, a means for applying a curing fluid to the coated wall.

A still further object of the invention is the provision of positive and efficient means for guiding the apparatus through the pipe line and maintaining it in a pre-set course.

Other features of the invention reside in the construction and arrangement of parts herein-after described, and particularly pointed out in the appended claims.

In the accompanying drawings:—

Figure 1 is a side elevation of my improved coating apparatus, the same being shown within a pipe line for treating the interior wall thereof with a protective coating. Figure 2 is a rear end view of the apparatus arranged within the pipe. Figure 3 is a front end view of the same likewise arranged within the pipe. Figure 4 is an enlarged, central longitudinal section of the apparatus showing the same in operation in a pipe line. Figure 5 is an enlarged transverse section taken substantially in the plane of line 5—5, Figure 4, and showing the retractable trowel mechanism. Figure 6 is a view similar to Figure 3, but showing the machine in a pre-set position for traveling through the pipe line with its traction wheels at one side of the vertical center plane of the pipe line. Figure 7 is a fragmentary, top plan view of the means for guiding the machine through the pipe wall. Figure 8 is a detail view of one of the trowel actuating rocker elements. Figure 9 is a plan view of the trowel-actuating control lever and associated parts. Figure 10 is a sectional view showing a modified arrangement of the fluid spray element.

Similar characters of reference indicate corresponding parts throughout the several views.

While my apparatus may be employed for coating different kinds of work, it has been primarily designed for treating the inner walls of steel pipe lines with a protective coating, such for example, as a plastic-like material as concrete. To this end, the apparatus consists generally of a carriage which is adapted to be propelled through the pipe line and which carries the working parts of the apparatus, such working parts comprising essentially a hopper or container for the coating material having a conduit or cylindrical feed chamber connected therewith; means for conveying the material from the hopper and through the conduit; a dispensing or discharge head into which the material is delivered from the conduit and from which it is discharged by centrifugal force onto the pipe wall; means for troweling the material after it has been applied to the pipe wall including actuating means for shifting the trowels into and out of engagement with the pipe wall; means for delivering onto the coated material a fluid spray having curative properties; and means for guiding the machine in a predetermined course through the pipe line, whereby the traction wheels of the machine can clear any obstructions, such as seams, rivets, etc., present in the pipe line and whereby the machine will travel in a pre-set course without the attention of the operator.

Referring now to the drawings, 10 indicates a section of the steel pipe line through which my apparatus is designed to travel for treating or coating the inner wall thereof with a covering of concrete or like plastic or semi-solid material. The carriage of the apparatus, which carries its working parts, may be of any appropriate construction, that shown in the drawings consisting of a structural steel frame 11 provided at one end with traction or supporting reels 12 and at its opposite end with a steering wheel or caster 13 mounted on a swiveling fork 14 suitably supported centrally of the frame. Motion is transmitted to the traction wheels from an electric motor 15 mounted on the carriage-frame, the drive from the motor consisting, for example, of a chain drive 16 to a counter shaft 17 and thence by a worm 18 and worm wheel 19 to the axle 20 of the traction wheels, a speed-reducing transmission 21 of any appropriate design being interposed between the motor and the chain drive for the purpose of propelling the carriage through the pipe at different speeds and thereby govern the thickness of the coating material applied to the pipe wall. For the purpose of this description, the traction wheels 12 may be considered as mounted at the rear end of the machine and the steering

wheel 13 arranged at the front end of the machine.

Mounted on the carriage-frame 11 is a feed hopper or container 22 for the coating material, and communicating with this hopper is a feed conduit, chamber or passage 23 which is disposed lengthwise and centrally of the machine and approximately axially of the pipe. Extending through this hopper and its communicating conduit is a tubular shaft 24 which is journaled at one end in the end wall of the hopper and at its opposite end in a closure plate or plug 25 fitted in the rear end of the conduit 23. Applied to this shaft is a screw conveyor 26 or like feed element which forces the material through the hopper and its communicating conduit 23. This screw conveyor shaft is driven at a comparatively slow speed by the motor 15, as, for example, by a driven shaft 27 and suitable speed-reducing gearing 28, 29.

The means for dispensing or discharging the coating material by centrifugal force and impacting it onto the pipe wall is preferably constructed as follows:—

At its rear end or discharge end the feed conduit 23 is provided with an annular row of discharge ports 30 which may be disposed in a more or less tangential fashion to permit the ready discharge of the material from the conduit. Surrounding the rear end of the conduit and in concentric spaced relation about the discharge ports 30 is a revolving tubular member 31 which may be journaled in suitable bearings 32 applied to the rear end of the carriage-frame 11. Formed between the ported end of the conduit 23 and the revolving member 31 is an annular chamber 33 into which the material is directed from the discharge ports and from which it is discharged onto the pipe wall. For effecting the discharge of the material from this chamber onto the pipe wall, a plurality of radial discharge nozzles, jets or pipes 34 are provided which are disposed in more or less contiguous relation about the tubular member 31 and revolve therewith at a comparatively high speed, whereby the plastic-like material is discharged from these jets in comparatively thin sheets or streams with the result that it is impacted against and distributed uniformly and evenly over the pipe wall. A suitable closure ring 35 may be applied to the rear end of the chamber between the feed conduit 23 and the tubular member 31, and air inlets 36 are provided which open into the chamber 33 for the purpose of delivering air thereto, the air being drawn into the same by the centrifugal force created by the revolving jet-carrying member 31 and acting to agitate the coating material and to discharge it from the jets in the form of a stream-like mass. The tubular member 31 which carries the revolving jets 34 may be rotated from the motor 15 through the medium of a belt and pulley 37. For the purpose of keeping the coating material at its proper consistency and for directing it outwardly through the discharge ports 30, the rear end of shaft 24 has blades or paddles 38 thereon.

The troweling mechanism for smoothing out the coating material after it has been applied to the pipe wall preferably consists of two oppositely revolving units constructed as follows:—

Each of these troweling units are identical in construction, one being associated with a revolving member 39 which rotates in one direction and the other being associated with a revolving member 40 which rotates in the opposite direction, the revolving member 39 being connected to a tubular shaft 41 extending through the screw-conveyor shaft 24 and the companion member 40 is applied

to a tubular shaft 42 which is telescoped within the companion shaft 41. The shafts 41 and 42 are driven by the driven shaft 27 through the medium of suitable gearing 43, 44 and 45, 46, respectively. Inasmuch as the trowel units themselves are identical, a description of one will suffice for both, each unit preferably consisting of diametrically-disposed radial arms 47 applied to the revolving member 39 or 40 and pivotally mounted at 48 on each of these arms is a vertically swinging trowel-carrying lever 49 to which is secured a trowel 50 which may be somewhat curved, as shown in Figure 5, so that its convex outer surface bears against the coating material on the pipe. For the purpose of adjusting the trowel-carrying levers to accommodate pipes of varying diameters, the arms 47 may be provided with a series of openings 51 for receiving the corresponding pivots 48 of said levers. Springs 52 between the levers 49 and the adjoining portions of the arms 47 serve to constantly urge the trowels into yielding engagement with the pipe wall, these springs being adjustably connected to the levers so as to create the proper tension thereon and accordingly exert the proper pressure on the material applied to the pipe wall. To accommodate the trowel to any unevenness of the pipe wall, such as produced by rivet heads, it may be cut or slit in the direction of its length to provide a series of spring tongues 53 whereby different sections of the trowel may yield in accordance with their encountering uneven areas on the pipe wall.

Means are also provided for shifting the trowels into and out of engagement with the pipe wall, and for this purpose I preferably provide means associated with each trowel unit for simultaneously controlling them from the front end or operator's station of the machine. To this end, I provide cam and leverage means for swinging the levers 49 about their fulcrums to bring the trowels into operative engagement with the pipe wall or to retract them therefrom. The cam means preferably consist of axially-shiftable, substantially conical-shaped drums, spools or collars 54 and 55 which are disposed side by side between the oppositely-revolving trowel units and axially of the shaft 42. These conical drums may be jointly mounted on a sleeve 56 encircling the shaft 42 and connected by a split or forked pin 57 with an axially-shiftable tubular shaft 58 telescopedly fitted within the shaft 42, said pin passing through longitudinal slots 59 formed in the diametrically opposite walls of said shaft 42, as seen in Figures 4 and 5, and the ends of these slots limiting the axial movement of the shaft 58 and the conical drums 54, 55. The shaft 58 and drum-sleeve 56 are adapted to turn with the shaft 42 for this purpose the first-named shaft has flat faces 60 which are adapted to be straddled and engaged by the forked pin 57 in the manner shown in Figure 5. The conical drum 54 is the actuating element for the trowel-levers associated with the revolvable member 39 while the companion drum 55 is associated with the oppositely rotating member 40 and in this connection the drum 55 is fixed on the sleeve 56 to revolve therewith while the drum 54 is loosely mounted on said sleeve and free to turn independently thereof. Cooperating with these drums to be actuated thereby in response to the axial movement of the shaft 58, and in turn effect the movement of the trowel levers 49 toward and from the pipe wall, are rocker members 61 which are pivoted at 62 to the revolving member 39 or 40 to swing in a plane transversely of the pipe, one arm of each

- rocker having a roller 63 thereon which engages the surface of the corresponding conical drum, while the other arm thereof is connected by a link 64 with the companion trowel-carrying lever 49. 5 The shiftable shaft 58 extends at its front end beyond the shaft 42 and is provided with a swivel thrust bearing block or collar 65 to which is connected a horizontally-swinging actuating lever 66 pivoted at 67 to an adjoining part of the carriage-frame. By this construction, when the actuating lever 66 is swung forwardly to shift the shaft 58 in the corresponding direction, the conical drums 54, 55 swing the rockers 61 in a direction to pull the corresponding levers 49 inwardly 10 to withdraw their trowels 50 from engagement with the pipe wall. For the purpose of latching the parts in this position, the drums are provided at their larger ends with annular grooves 68 into which the rocker rollers 63 are adapted 15 to seat and thereby prevent accidental displacement of the parts in the contracted positions of the trowels. Upon moving the lever 66 rearwardly or in the opposite direction, the conical drums actuate the rockers in a direction to project the levers 49 outwardly to bring their trowels into 20 yielding engagement with the pipe wall.

It is desirable when applying a coating of concrete to a pipe wall to also treat the same with a curing fluid, such for example as asphaltum, 25 which holds the moisture in the concrete, and for this purpose the tubular shaft 58 serves to convey the asphaltum to one or more spray jets or nozzles 69 applied to the rear end of the said shaft 58 beyond the troweling mechanism, as 30 seen in Figure 4. The front end of this tubular shaft is connected by a flexible pipe 70 with a container 71 mounted on the carriage-frame and containing a supply of the fluid material. In 35 practice air pressure may be exerted on this fluid to direct it toward the spray jets 69 and thence by centrifugal force onto the pipe wall, it being understood that the tubular shaft 58, to which said jets are connected, rotates with the shaft 42 through the medium of the coupling pin connection 57.

If desired, a separate drive unit may be provided for applying the liquid material to the coated pipe wall and I have shown such a modification in Figure 10, wherein 72 indicates the fluid supply tube corresponding to the hollow shaft 58 of the previously described construction and having ports 73 at its discharge end which communicate with a revolving spray head or chamber 74 having one or more jets 75 at its periphery. 50 This spray head is revolved at a high speed by a self-contained driving mechanism preferably in the form of an electric motor mounted on the rear end of the supply tube 72 and including a stator element 76 and a rotor element 77 to which 55 said spray head is connected. In its side the annular spray head has an opening 78 which allows air to be admitted thereto for augmenting its spraying action and which also permits of cleaning or washing the interior of the head when 60 necessary.

In addition to the trowels 50 I preferably provide auxiliary or finishing trowels 79 which are disposed in trailing relation to said trowels 50 and may be offset relative thereto to smooth out 65 any marks or ridges left by the main trowels. As seen in Figure 5, each auxiliary trowel is carried by a yieldable arm or shank 80 fixed at its inner end to the corresponding trowel-carrying lever arm 47. The yieldability of the shank 80 constantly urges the trowel against the pipe-wall 70

and when the main trowels are contracted their blades or adjoining portions contact with the finishing trowel or its shank and likewise withdraw the same from the pipe wall.

The means for guiding the carriage in a pre-determined course through the pipe line are so designed as to automatically maintain the machine in a pre-set course with its coating material dispensing head disposed axially of the pipe line even though the machine traction wheels 10 12 are displaced somewhat at an angle to the horizontal, as depicted in Figure 6, as when it is desired that such wheels clear the row of rivets or like obstructions present in the pipe line, so that the machine will travel smoothly there-through and will not bump along and interfere with the coating operation of the pipe. Such means preferably consist, as shown in Figures 1, 3, 6 and 7, of a manually-controlled, laterally shiftable steering lever 81 pivoted at 82 to the 15 front end of the carriage-frame 11 and traversing a quadrant 83 which serves to hold the lever in a pre-set position. Depending from the free end of the lever and pivoted at 84 to a hanger 85 suspended therefrom is a laterally-swinging 20 pendant bar or pendulum 86 having a weight 87 at its lower end which tends constantly to maintain said bar in a vertical position, and which is operatively connected, as by a rod 88, to the steering wheel fork 14. By this construction, 25 while the machine may be steered to clear, say a row of rivets in the pipe line, the pendulum will act automatically through said rod 88 to return the wheel-fork to its normal position and thereafter maintain the wheel 13 in a straight course 30 even though the machine may be tilted to the horizontal and radially of the pipe.

I claim as my invention:

1. An apparatus for lining pipe walls, comprising a supporting frame having a feed conduit applied thereto and adapted for communication at one end with a source of coating material, a revolving dispensing member disposed at the discharge end of said conduit for delivering the material to the pipe wall, means for conducting the material through the conduit to said dispensing member, a retractable revolving trowel for smoothing down the material after it has been deposited on the pipe-wall, and means for shifting said trowel into and out of engagement with the pipe-wall including an actuating member extending through said conduit and having an operating handle at one end and means at its opposite end connected with said trowel.

2. An apparatus for lining pipe-walls, comprising a supporting frame having a feed conduit applied thereto and adapted for communication at one end with a source of coating material, a revolving dispensing member disposed at the discharge end of said conduit for delivering the material to the pipe-wall, means for conducting the material through the conduit to said dispensing member, a retractable revolving trowel for smoothing down the material after it has been deposited on the pipe-wall, and means for shifting said trowel into and out of engagement with the pipe-wall including an actuating member extending through said conduit for axial movement relative thereto and having an operating handle at one end thereof, and means at the opposite end of said member and operatively connected to said trowel for actuating the same, in response to the movements of said actuating member, into and out of operative engagement with the pipe-wall.

3. An apparatus for lining pipe-walls, comprising a supporting frame having a feed conduit applied thereto and adapted for communication at one end with a source of coating material, a revolving dispensing member disposed at the discharge end of said conduit for delivering the material to the pipe-wall, means for conducting the material through the conduit to said dispensing member, oppositely revolving arms disposed in adjoining relation beyond said dispensing member and having retractable trowels applied thereto for smoothing down the material after it has been applied to the pipe-wall, a reciprocating actuating element extending axially through said conduit and having an operating handle at one end for controlling its movement, and means at the opposite end of said actuating element including connections to said trowels for shifting them into and out of operative engagement with the pipe-wall.
4. An apparatus for lining pipe-walls, comprising a supporting frame having a feed conduit applied thereto and adapted for communication at one end with a source of coating material, a revolving dispensing member disposed at the discharge end of said conduit for delivering the material to the pipe-wall, means for conducting the material through the conduit to said dispensing member, a revolving retractable trowel disposed beyond said dispensing member for smoothing down the material after it has been deposited on the pipe-wall, a combined reciprocating actuating element and feed tube for a fluid material extending axially through said conduit and terminating at its discharge end beyond said trowel in a spray nozzle for applying said fluid material to the coated pipe-wall, and means at the opposite end of said actuating element including connections to said trowel for shifting it into and out of operative engagement with the pipe-wall.
5. An apparatus for lining pipe-walls, comprising a supporting frame having a feed conduit applied thereto and adapted for communication at one end with a source of coating material, a revolving dispensing member disposed at the discharge end of said conduit for delivering the material to the pipe-wall, means for conducting the material through the conduit to said dispensing member, oppositely revolving arms disposed in adjoining relation beyond said dispensing member and having retractable trowels applied thereto for smoothing down the material after it has been applied to the pipe-wall, a feed tube for a fluid material extending axially through said conduit for axial movement relative thereto, said tube having an operating handle at one end for controlling its movement and means adjacent the opposite end thereof including connections to said trowels for shifting them into and out of operative engagement with the pipe-wall, said tube terminating beyond said trowel-shiftable means in a spray nozzle for applying said fluid material to the coated pipe-wall.
6. In an apparatus of the character described, a rotatable member, a lever pivoted to said member to swing substantially in the plane thereof, a trowel applied to said lever, and cam-like means movable in a direction axially of said rotatable member and having an operative connection to said lever to swing the same and its trowel radially inward and outward.
7. In an apparatus of the character described, a rotatable member, a lever pivoted to said member to swing substantially in the plane thereof, a trowel applied to said lever, a substantially conical-shaped actuating cam movable in a direction axially of said rotatable member, and a contact element engaging said actuating member and operatively connected to said trowel-carrying lever to swing the same radially toward and from the axis of said rotatable member.
8. In an apparatus of the character described, a rotatable member, a lever pivoted to said member to swing substantially in the plane thereof, a trowel applied to said lever, a substantially conical-shaped actuating cam movable in a direction axially of said rotatable member, a contact element engaging said actuating member and operatively connected to said trowel-carrying lever to swing the same radially toward and from the axis of said rotatable member, means for reciprocating said actuating member axially relatively to said rotatable member, and means for yieldingly urging the trowel-carrying portion of said lever in an outward direction.
9. A troweling mechanism for pipe-coating apparatus, comprising an axially-shiftable support, a member rotatably mounted thereon, a lever pivoted to said member to swing toward and from the pipe-wall and having a trowel applied thereto, a substantially conical-shaped cam mounted on said member and connected to said axial support for axially shifting movement therewith, oscillatory means applied to said rotatable member and in bearing contact with said cam at one end and operatively connected at its other end to said trowel-carrying lever, and means for actuating said axially-shiftable support in one direction or the other to swing said lever toward and from the pipe-wall.
10. A troweling mechanism for pipe-coating apparatus, comprising an axially-shiftable support, a member rotatably mounted thereon, a lever pivoted to said member to swing toward and from the pipe-wall and having a trowel applied thereto, a substantially conical-shaped cam mounted on said member and connected to said axial support for axial shifting movement therewith, a second lever fulcrumed on said rotatable member and having one arm thereof in contact with said cam to be actuated thereby and the other arm being link-connected to the trowel-carrying lever, and means for actuating said axially-shiftable support in one direction or the other to bring the trowel into and out of engagement with the pipe-wall.
11. A troweling mechanism for pipe-coating apparatus, comprising a pair of oppositely rotatable members, trowels applied to said members, respectively, for movement into and out of engagement with the pipe-wall, and means for simultaneously shifting said trowels into and out of engagement with the pipe-wall.
12. A troweling mechanism for pipe-coating apparatus, comprising a pair of oppositely rotatable members, trowels applied to said members, respectively, for movement into and out of engagement with the pipe-wall, and complementary inter-engaging cam and rocker means for shifting said trowels into and out of engagement with the pipe-wall.
13. A troweling mechanism for pipe-coating apparatus, comprising a pair of oppositely rotatable members, trowels applied to said members, respectively, for movement into and out of engagement with the pipe-wall, and complementary inter-engaging cam and rocker means for shifting said trowels into and out of engagement with the pipe-wall, said cam being disposed for move-

ment in a direction axially of said rotatable members and said rocker means being oscillated thereby in a plane at substantially right angles to such axis to actuate the trowels.

- 5 14. In an apparatus of the character described, the combination of a rotatable hollow shaft mounted for limited axial movement in opposite directions and adapted for communication at one end with a source of fluid material and provided at its opposite end with a spray jet for delivering such material onto a pipe-wall, a member rotatably mounted on said shaft and having a retractable trowel applied thereto for movement into and out of engagement with the pipe wall, means 10 for manually shifting the hollow shaft, and means governed by the axial movement of said hollow shaft for controlling the movement of said trowel.
- 15 15. In an apparatus of the character described, the combination of a rotatable hollow shaft mounted for limited axial movement in opposite directions and adapted for communication at one end with a source of fluid material and provided at its opposite end with a spray jet for delivering such material onto a pipe-wall, a member rotatably mounted on said shaft and having a retractable trowel applied thereto for movement into and out of engagement with the pipe wall, means 20 for manually shifting the hollow shaft, and means governed by the axial movement of said hollow shaft for controlling the movement of said trowel.
- 25 30 35 40 16. A troweling mechanism for pipe coating apparatus, comprising a rotatable member, a lever pivoted thereto to swing crosswise of the pipe, a main trowel applied to said lever, and an auxiliary trowel pivoted to said rotatable member and connected at one end with said conical element and connected at its other end to said trowel.

ber and having its blade in trailing relation to the blade of said main trowel.

17. A troweling mechanism for pipe coating apparatus, comprising a rotatable member, a lever pivoted thereto to swing crosswise of the pipe, a main trowel applied to said lever, means for yieldingly urging said trowel-carrying lever in a direction toward the pipe-wall, and an auxiliary trowel pivoted to said rotatable member and having its blade in trailing relation to the blade of said main trowel, the auxiliary trowel having a yieldable shank in contact with said lever to be urged thereby toward the pipe-wall.

18. The combination with a pipe coating machine including a wheeled carriage adapted to travel through the pipe and having a revolvable discharge head for delivering the coating material onto the pipe wall, and means for guiding said carriage through the pipe and maintaining said discharge head axially of the pipe, said means consisting of a caster wheel disposed centrally at one end of the carriage, a laterally-swinging adjusting lever, and a pendulum-like element suspended from said lever to swing laterally and operatively connected to said wheel to maintain the machine in a definite pre-set course through the pipe.

19. The combination with a pipe coating machine having traction wheels at one end and a centrally disposed steering wheel at its other end including a swivel supporting frame therefor having a steering rod projecting therefrom, of a horizontally swinging lever pivoted centrally of said frame and having a hanger depending from its free end, a pendulum fulcrumed on said hanger to swing laterally and operatively connected below its fulcrum to said steering rod to automatically maintain the steering-wheel in a straight set position.

ALBERT G. PERKINS.
